DESIGN FOR A SCARF

Abraham M. Goldberg, Denver, Colo.

Application August 23, 1946, Serial No. 132,786

Term of patent 14 years

(Cl. D3—12)

To all whom it may concern:

Be it known that I, Abraham M. Goldberg, a citizen of the United States, residing in the city and county of Denver, State of Colorado, have invented a new, original, and ornamental Design for a Scarf, of which the following is a specification, reference being had to the accompanying drawing, forming part thereof.

The figure is a face view of a scarf, showing my new design, the reverse side of the scarf being unornamented.

I claim:

The ornamental design for a scarf, as shown and described.

ABRAHAM M. GOLDBERG.
